(No Model.)

H. M. COX.
CAR COUPLING.

No. 603,176.

Patented Apr. 26, 1898.

UNITED STATES PATENT OFFICE.

HENRY M. COX, OF LINDEN, CALIFORNIA, ASSIGNOR TO THE INTERNATIONAL AUTOMATIC CAR-COUPLER COMPANY, OF SAN JOAQUIN COUNTY, CALIFORNIA.

CAR-COUPING.

SPECIFICATION forming part of Letters Patent No. 603,176, dated April 26, 1898.

Application filed November 13, 1897. Serial No. 658,490. (No model.)

To all whom it may concern:

Be it known that I, HENRY M. COX, a citizen of the United States, residing at Linden, in the county of San Joaquin and State of California, have invented certain new and useful Improvements in Car-Couplers; and I do hereby declare the following to be a full, clear, and exact description of the invention, such as will enable others skilled in the art to which it app-
10 pertains to make and use the same.

The invention relates to that class of automatic car-couplers in which there are two links connected by two metal pins passed through a sleeve in a movable slide, said links being held in place by a pin or bolt which is passed through the solid metal of the head.

The object of the invention is to so combine the two coupling-links that after being coupled they form a double link, thereby giving 20 double strength, as well as to be automatic and save handling when cars are coupled together.

A further object of the invention is to provide for the use of four pins instead of two, as 25 is usual, also to form a link-coupling by means of which the coupler is relieved from friction when the trains are on curves, as well as to preserve the utility of the coupling if one of the pins should be broken.

30 I accomplish these results by the mechanism hereinafter described, and illustrated on the accompanying drawings, forming a part of this specification, and on which—

Figure 1 is an elevation of the two parts of 35 the device, one in side elevation and the other in vertical section and in position to be coupled. Fig. 2 is a vertical central section showing the links coupled. Fig. 3 is a front elevation of one part of the coupler. Fig. 4 is 40 a plan view of the parts coupled, and Fig. 5 shows the arrangement of the springs when a sliding sleeve is used.

Like letters of reference indicate corresponding parts in the different views.

45 C are the heads of the coupler, and as the two are counterparts or duplicates it is only necessary to describe one of them. The head C is of metal and of suitable form to be secured to the car or the buffer thereof, and it 50 may be formed as an element when the car is

built. A socket for the link extends inward a suitable distance from the front end of the head C. This socket is to receive the links and has a flaring mouth, as usual, so that the links will be easily and readily inserted there-
55 in and have some play. The walls of the head have apertures M, through which the coupling-pin is passed to couple the links.

E is a metal slide, shown on the drawings as adapted to be moved a limited distance in 60 suitable ways on top of the head-block.

The slide E has a sleeve F at its front end to secure and partially support the coupling-
65 pin. The slide is also slotted to allow of a limited movement of the same horizontally 70 against the action of a spring.

The spring J surrounds a rod or bar K, projecting from the rear or heel end of the slide E, and the rear end of the spring abuts against a shoulder formed on the top of the head, 70 while the pin or rod extends into a lateral recess in the shouldered part of the head when the slide E, which in its normal position extends beyond the front face of the head, is pushed back to couple the links.

75 The slide E is secured to the head so as to slide thereon by depending feet at each side connected at the bottom by a cross-bolt O or by means of a flange on the head C, or it may be a sleeve extending around said head and 80 may have the spring or springs at the top, sides, or bottom, as may be preferred, as shown in Fig. 5.

A vertical bolt G passes through the slot L in the slide E and is secured by means of a 85 nut on the under side of the head. This bolt also secures the coupling-link loosely in the socket in the head and prevents it from falling out.

The slot in the plate or slide E bears such 90 relation to the vertical apertures through the top and bottom walls of the head that when the slide is in its normal position the coupling-pin will be supported on the solid part of the head, and when the cars come together 95 the concussion or impact will push back the slide E until the lower end of the coupling-pin H is coincident with the holes or apertures M, when the pin drops down by gravity and couples the links.

The links D are oval or rectangular in form and are wedge-shaped, the thinnest or attenuated end projecting from the sockets in the head.

- 5 The pin H may be formed with a shoulder, if desired, to prevent it from falling out of the sleeve F, and it may be provided with a suitable lever, to be operated from the side or top of the car, for uncoupling, or it may be secured by means of a chain to prevent it from falling to the ground when it is desired to uncouple by hand.

The heads, at their front ends, are preferably somewhat rounded, so that when two cars are coupled they will allow some lateral movement when a train is going around a curve.

The operation of the coupler will be fully understood from the foregoing description.

- 20 The coupling operation is automatic, and the uncoupling is performed by withdrawing the coupling-pin either by hand or by means of a suitable lever.

The form of the links—viz., of wedge shape—makes a stronger coupling, and each link is held by two pins—that is to say, the coupling-pins and the bolt that secures the link in place—and if either pin should accidentally be broken the link will be held by

- 30 the remaining pin.

Minor changes may be made in the structure, within the scope of the invention, without departing from the spirit or sacrificing any of the advantages thereof.

- 35 Having thus fully described the invention, what I claim as new, and desire to secure by Letters Patent, is—

1. A car-coupler having a socketed head with vertical apertures therethrough, a slotted sliding plate on top of the head provided

with a sleeve and which normally projects beyond the front face of the head, a coupling-pin supported in said sleeve with its lower end resting on the solid part of the head for automatic coupling, a wedge-shaped link and a vertical bolt passed through the head link and sliding plate, substantially as described.

2. A car-coupler having a socketed head with vertical apertures therethrough, a slotted sliding plate on top of the head provided with a sleeve and which projects normally beyond the front face of the head, a spring between the head of the sliding plate and a shoulder on the socketed head, a coupling-pin supported in said socket-sleeve with its lower end resting on the solid part of the head for automatic coupling, a wedge-shaped link, and an independent bolt which is passed through the head, link and the slot in the sliding plate, substantially as described.

3. A car-coupler having a socketed head with vertical apertures therethrough, a slotted sliding plate which normally projects beyond the front face of the head, a rod or bar on the head of the plate, a spring surrounding said rod and resting against a shoulder on the head, a sleeve on the sliding plate, a coupling-pin supported in said sleeve with its lower end resting on the solid part of the head for automatic coupling, a wedge-shaped link, and an independent bolt which is passed through the head, link and slot in the sliding plate, substantially as and for the purposes described.

In testimony whereof I affix my signature in presence of two witnesses.

HENRY M. COX.
